S. Slater.
Threshing Mach.

Patented Oct. 1, 1830.

Oct 1 1830 6163x 221.

Samuel Water, Northern Liberties, Philadelphia.

Letters Patent.

The schedule referred to in these Letters Patent, and making part of the same, containing a description in the words of the said Samuel Water himself of his improvement in the Machine called Water's Threshing and Winnowing Machine.

To all persons to whom these presents shall come,
I Samuel Water of the Northern Liberties in the County of Philadelphia, State of Pennsylvania, Artist, send greeting. Be it known that I Samuel Water have invented, discovered, and applied to use, various new and highly useful improvements in a machine called known as Water's Threshing and Winnowing Machine, for the purpose of threshing and cleaning all kinds of small grain, and particularly that of rice; A fan is connected with the machinery, that completely separates the straw and chaff from the grain at the same operation. It has also the desirable effect of expelling the dust from the person who attends the machine; without that improvement the dust would be a great inconvenience to the operator, which has from practical experience been pronounced superior to any machine, heretofore known or invented. A.A. The frame, made of scudding of either hard or soft wood, or of metal, if of wood scudding, five inches square iron in proportion, about six feet in length, and from two to three in width; the frame standing in the front two feet six inches in height, in the rear about four feet which gives it the position of an inclined plane; the above is calculated for a total twenty seven inches in length, which will be hereafter described. B.B. The girdles and timbers near the bottom, running from the back to the front posts on each side, and from each post to the other; in front is a girdle within ten inches of the top, extending across the two corresponding front posts, which are secured by short bolts, on which rests the mouth of

the

Drawing.

the form. C. The front posts, are about eighteen inches shorter than the rear posts which are about four feet in height. D. The inclined plane or flooring for the grain in the box by which it is conducted to the feeding rolls, is made of pine or other wood as is the floor, of sufficient length to contain the longest sheaf of grain in the box, which is represented in the cut E, F. The feeding rolls, are constructed of wood or iron, if made of wood and iron it is necessary to have a wooden cylinder about three inches in diameter, fitted out in eight or ten places or more, half an inch in depth to receive pieces of common horse hair set in edgeways, leaving it projecting out one fourth of an inch which will conduct the shears to the beater. The feeding rolls have a shaft or guideship passing through the ends and extending along the frame, of sufficient length to admit the bearings and pulleys; the said pulleys are about four inches in diameter and grooved on the edge to admit a wooden band that connects with the drawing pulley on the main wheel shaft. F. The main balance wheel shaft, one and three quarter inch in diameter, extending along the frame of the machine twelve inches clear on the left hand side, which is turned with bearings, secured by bolts and fastened to the frame. The caps to the said bolts have a cup or cavity which will contain about half a gill of oil, and a wiper at the bottom which gradually falls upon the guideship, the moisture of which is a complete prevention from heat or friction. G. The pulley on the projecting shaft, nine inches in diameter, turned with grooves and connected with band to drive the feeding rolls, which can be increased in size to give any required speed. H. The balance wheel about six feet in diameter connected with the aforesaid drawing pulley on the before mentioned projecting shaft; the weight of the wheel is about two hundred pounds. The design of this is to keep the momentum of the beater up, which will prevent the latter from checking the velocity of the beater, which is

all important in threshing the grain and cleaning it, is a man not heretofore known or done by any machinery.

L. The belt which around the main wheel that drives the whirl or pulley attached to the beater. See cut. It may also be constructed with a belt to conform with the figure or head of office, thus which will prevent the band from popping off the wheel, or running at random; the band must pop two or three times round the wheel extending to the whirl, in a like manner on the shaft of the beater there to be placed two or three times round it to prevent it from slipping. M. A pulley attached to the main balance wheel eight inches in diameter and may be used with either belt or band leading to the horse power; which may be constructed in the same manner as the aforementioned balance wheel. N. The beater or cylinder, is twenty seven inches in length, constructed with a shaft about one and three quarters of an inch in diameter, made of iron turned with bearings and projecting over both sides for the reception of the driving pulleys, which are secured to the frame by boxes and caps as explained under the letter E. The beater is about ten or twelve inches from the front of the frame the beater or cylinder is made of wood eight inches in diameter inches including the beater which are iron set in grooves of half an inch, which have tenons on each end, on which is a head of wrought or cast iron with mortises to receive them. This is the head of the cylinder, See cut; the said beater which is in front of the feeding tolls also in the front part of the machine beats the grain upwards against the concave, while the fan or cleaning machine acts beneath. O. The concave, is a cylinder of cast iron, which covers about one third of the beater, with grooves on the inside which act as a rubber against the beater; the concave rests on the frame, has heads at each end, it comes in contact in within the eighth part of an inch of the beater secured by wooden springs resting on the top. See cut; there is also a projecting ear or piece of iron, one and a half inch on each end of the concave which

which is or may be secured by a bolt passing through a plate being
and secured on the under side with a nut, which is a substitute
or improvement for the wooden springs before mentioned. These
springs are very material; they give the machinery a good and
operation, rising and falling suitable to the quantity of grain in
the feeder. N. The fan before mentioned is connected with the
machine secured to the frame under the floor or apron; - The fan is
constructed with a shaft made of iron piping through the cylinder
or covering of the fan and projecting over on the right hand
side to receive a pulley of a size calculated to reduce the velocity
to that of one fourth of the beater; - The cylinder is a cover or plow
the air passes in at the head, and is conducted by the motion of
the fans or wings in the beater to the under side, where the grain
passes out. ~~Breaks~~ ^{Breaks} - Recapitulation. The frame for the beater
twenty seven inches in length, eight in diameter, making twenty
two inches including the iron beaters; The frame is also twenty
seven inches in width in the clear, six or eight feet in length, the
near or back posts about four feet high, the front posts about
thirty inches, the front and back posts about five feet apart
the floor inclining to give the grain a free and easy pitch to the
feeding rolls to pass it to the beaters; The beaters may be propelled
the velocity of from sixteen hundred to two thousand revolutions
in a minute, it is a quick lively blow that threshes the grain down;
there are six beaters which strike the grain from nine to twelve hours
sand twice a minute. A fan constructed on the inside, with an
conductor on the under side of the beater to separate and clean the
grain from the straw as it drops from the beater; a cover or plow
over the beater about a third of a circle, kept in its place by
bolts and springs. It also has a horse power of the usual con-
struction. The difference between the plan and operation
this threshing and winnowing or cleaning machine, consists
in this, that is to say: in the first place, The machine is con-
structed with a board flooring instead of a cloth floor, which
is

is now used, the hand of laboring men over the proper and
better than the existing open, and is at the same time less
expensive and not liable to want of firing, or being injured.

4th, The beater revolving or throwing the dust from the straw
according the machine, which is not the case in any former inven-
tion. - 5th, The simplicity of the case. 6th, The straw, having
coming in contact with the beater, which prevents the straw
from tangling round the beater and separating the grain from
the straw. - 5th, The whole machine is more simple and
precise in its operations, much better calculated for the use
than any now in use, durable and easily constructed, the price
considerably less than others, which afford no competition with
the above described. 6th, The machine is also admirably
calculated for threshing rice. The claims are the genuine
merits of the machine. In testimony that the foregoing
is a true specification of my said machine, as above described,
I have hereunto set my hand and seal, at Philadelphia in the state
of Pennsylvania, this third day of July in the year of our Lord one
thousand eight hundred and thirty, 1830.

Witnessed
